FIG. 1.

Inventor:
Henry Warden
by his Attorney
Howard and Son

UNITED STATES PATENT OFFICE.

HENRY WARDEN, OF PHILADELPHIA, PENNSYLVANIA.

FEED-WATER HEATER.

SPECIFICATION forming part of Letters Patent No. 352,379, dated November 9, 1886.

Application filed November 2, 1885. Renewed August 23, 1886. Serial No. 211,649. (No model.)

To all whom it may concern:

Be it known that I, HENRY WARDEN, a citizen of the United States, residing in Philadelphia, Pennsylvania, have invented certain improvements in Feed-Water Heaters, of which the following is a specification.

One object of my invention is to so construct a feed-water heater as to cause a slow and uniform circulation of the water therein, so as to obtain the best heating effect and insure the proper deposition of the impurities contained in the water, a further object being to provide for the removal of the sediment and scum from the heating-chamber.

15 In the accompanying drawings, Figure 1 is a longitudinal section of a feed-water heater constructed in accordance with my invention; Fig. 2, a transverse section of the same; Fig. 3, a perspective view of part of the supply-pipe 20 of the heater and its distributor; Fig. 4, a perspective view of the scum-discharge pipe, and Figs. 5 and 6 views showing modifications of one feature of my invention.

A is the main portion of the shell of a heater, 25 which is in the present instance in the form of a cylinder, and is provided with opposite concavo-convex heads B B, between flanges on which are confined the outer portions of the plates 30 D D, which carry the heating-tubes F, a steam-inlet pipe being connected to a branch, a, on one head B, and an outlet-pipe to a similar branch, a', on the opposite head, so as to maintain through the tubes F a circulation of steam 35 for the purpose of heating the water. The latter enters the heating-chamber from a supply-pipe, G, which communicates with a distributing-pipe, J, located within the vessel A, close to the bottom of the same, and extending almost 40 from end to end of the heating-chamber.

In the top of the pipe J are slots b, these slots extending from the ends of the pipe almost to the center of the same, the pipe having a closed top directly over the mouth of the 45 feed-pipe, and the slots b being preferably tapered—that is to say, gradually decreasing in width from the ends toward the center of the pipe.

A collecting-pipe, M, of construction similar 50 to the distributing-pipe J, is arranged in the upper portion of the vessel A and communicates with the discharge-pipe N, so that the

cold water enters the lower portion of the heating-chamber in a thin stream or sheet extending throughout the length of said chamber, the heated water being drawn off from the top of the chamber in the same manner, whereby neither inlet nor discharge has sufficient force to cause the formation of a strong current from the inlet to the outlet, as is the case in that 55 class of heaters in which the inlet and outlet pipes have no distributing and collecting pipes within the heating-chamber.

The tapering slots of the distributing and collecting pipes insure the entrance or discharge of a practically uniform volume of water from end to end of the heating-chamber, because in those portions of the pipes farthest from the supply or discharge pipe the area of the slot is increased to such an extent as to 60 compensate for the decreased pressure in the pipe at such points. The water consequently ascends slowly and at a uniform rate in all 65 portions of the heating-chamber, ample time being thus afforded for the deposition of the 70 solid impurities contained in the water and for the rising of the lighter impurities in the 75 form of scum to the upper portion of the heating-chamber.

The tapering of the slots b need not be resorted to in all cases. For instance, the distributing or collecting pipe may be so much larger in area than the supply or discharge pipe that there will be a low and practically uniform pressure in all parts of said distributing or collecting pipe.

The solid impurities collecting in the lower portion of the heating-chamber are drawn off from time to time through a pipe, d, located close to the bottom of the chamber and having 80 a slot or perforations in its under side, a similar pipe, f, Fig. 4, having a slot or perforations in the upper side, being located close to the upper portion of the heating-chamber, and serving for the discharge of the scum which 85 accumulates therein.

Rows of perforations may be formed in the pipes J and M, instead of slots, as shown, for instance, in Fig. 5, these perforations being 90 preferably graduated in area in the same manner as the slot, and, if desired, the feed or discharge pipe may communicate with one end of the distributing or collecting pipe, instead of with the center of the same, as shown in Fig.

6; or there may be two or more feed or discharge pipes communicating with a single distributing or collecting pipe.

When it is not desired to heat the water in the vessel A, the pipes F and plates D may be dispensed with and the vessel used as a settling-chamber, the absence of a strong current insuring the effective separation of the impurities from the water, which may be heated either before passing through the vessel or after its passage, or both before and after the separating operation.

I claim as my invention—

1. The combination, in apparatus for purifying or heating and purifying feed-water, of the shell or casing of the feed-water vessel, an inlet-pipe having a distributor in the lower portion of the chamber within said casing, and a discharge-pipe having a collector in the upper portion of said chamber, both distributing and collecting pipes being slotted or perforated and providing extended areas for the inlet and discharge of the water, whereby the latter is caused to flow through the vessel without forming special currents, all substantially as specified.

2. The combination of the shell or casing of a feed-water vessel with a distributing or collecting pipe contained in the chamber within

said casing, and having a passage of differential area for the water, the area of the passage being greater at points remote from the inlet or discharge pipe than at points adjacent thereto, all substantially as specified.

3. The combination of the shell or casing of a feed-water vessel, a water-inlet pipe communicating with the chamber within said vessel at some distance above the bottom, a water-discharge pipe communicating with said chamber at some distance below the top, and scum and sediment discharge pipes located, respectively, near the top and near the bottom of said chamber, all substantially as specified.

4. The combination of a shell or casing of a feed-water vessel, and the inlet and discharge pipes for the water, with a slotted or perforated sediment-discharge pipe in the lower portion of the chamber within the casing, and a similar pipe in the upper portion of said chamber for the discharge of scum, all substantially as specified.

In testimony whereof I have signed my name to this specification in the presence of two subscribing witnesses.

HENRY WARDEN.
